Attorney

UNITED STATES PATENT OFFICE.

MAYNARD E. PENQUITE, OF COLFAX, IOWA.

SASH-FASTENER.

1,351,868.

Specification of Letters Patent.

Patented Sept. 7, 1920.

Application filed April 25, 1917. Serial No. 164,455.

To all whom it may concern:

Be it known that I, MAYNARD E. PENQUITE, a citizen of the United States, residing at Colfax, in the county of Jasper and State of Iowa, have invented certain new and useful Improvements in Sash-Fasteners, of which the following is a specification, reference being had to the accompanying drawings.

10 This invention relates to sash locks, and has for its primary object to provide a device of this character which is simple and inexpensive in its construction and may be operatively applied to the window sash without necessitating any structural alterations whatever in the sash or the window frame.

It is another and more particular object of the invention to provide a device of this character embodying a shiftable plate, and 20 cam means for urging said plate into binding engagement with the window frame at one side of the sash, whereby said sash may be securely locked and held in various adjusted positions in the frame.

25 It is another important object of the invention to provide a sash lock which is not accessible from the exterior of the window, and which may be advantageously used for holding the window sashes in closed position 30 when they become loose or the sash cords break.

And it is a further general object of the invention to provide a device as above characterized which can be used either upon 35 window sashes or doors as a detachable, auxiliary lock.

With the above and other objects in view, my invention consists in the novel features of construction, combination, and arrangement of parts to be hereinafter more fully described, claimed and illustrated in the accompanying drawings, in which,

40 Figure 1 is a perspective view showing my improved sash lock applied to the window sash in its operative position;

Fig. 2 is an enlarged horizontal sectional view; and

Fig. 3 is a section taken on the line 3—3 of Fig. 2.

45 Referring in detail to the drawing, 5 designates the body plate of the device which is constructed from a single, metal plate and is adapted to be attached to the face of the vertical sash stile by means of screws or other analogous fastening devices indicated

at 6. This plate is bifurcated, and the spaced arms 7 thereof are provided with angularly disposed terminals 8. The opposite end of the plate is provided with an outwardly pressed or offset, longitudinally extending, central portion 9 in which a stud bolt 10 is suitably fixed.

11 designates the locking plate which is of elongated form and is provided with an offset portion 12 longitudinally slotted, as 65 at 13. The offset 9 in the body plate 5 is disposed in this slot and serves as a guide for the locking plate. At the inner end of the slot 13, an angularly projecting lug 14 is formed upon the locking plate. A flange 70 15 is also disposed at right angles to the locking plate and projects in a relatively opposite direction from the lug 14.

16 designates a cam member which is loosely mounted on the stud bolt 10 between 75 the head 10' thereof and the slidably locking plate. This cam member is provided with suitable finger pieces, indicated at 17, whereby it may be conveniently turned or rotated.

80 As seen in Fig. 1 of the drawing, my improved locking device is applied to the sash with the lugs 8 extending over the outer edge of the sash stile, said plate being rigidly secured by means of the screws 6 to the inner 85 face of the stile. The flange 15 on the end of the locking plate 11 also extends over the edge of the stile. It will be understood that, if desired, one of the locking devices may be thus arranged upon each of the vertical 90 stiles of the window sash. After the sash has been adjusted to the desired position in the window frame, the cam plate 16 is rotated and the edge thereof bearing against the lug 14 forces the locking plate 11 outwardly or laterally from the sash stile so 95 that the flange 15 of said plate is urged into tight frictional bearing engagement against the base wall of the rabbet in the window frame. Thus, the sash will be securely 100 locked or held against further vertical movement in either direction. It will be observed that the device being located upon the inner side of the sash stile substantially midway between the top and bottom of the sash, is 105 not accessible from the exterior of the window, thus rendering the window sash substantially burglar-proof.

110 While I have illustrated my invention as applied to a window sash, it is manifest that

the same may also be advantageously used as an auxiliary locking device for doors. In such use the device need not be permanently attached to the door, but may be readily applied thereto by transient guests, by simply engaging the lugs 8 and flange 15 over the edge of the door and then operating the rotatable cam plate to tightly engage the flange 15 with the door frame. If one endeavoring to obtain entrance to the room should succeed in picking the lock, the door will, nevertheless, be held by means of my device against opening movement when subjected to ordinary pressure. The attempted intrusion will thus be frustrated as the would-be intruder will conclude that the door is securely locked by other means which is inaccessible.

From the foregoing description, taken in connection with the accompanying drawing, the construction, manner of operation and use and several advantages of the invention will be clearly and fully understood.

While I have herein shown and described the particular form and construction of the several elements employed, it is to be understood that the parts are susceptible of many modifications and I, therefore, reserve the privilege of adopting all such legitimate changes as may be fairly embodied within the spirit and scope of the invention as claimed.

Having thus fully described my invention,

what I desire to claim and secure by Letters Patent is:

A sash fastener comprising a flat body plate formed at one end with spaced legs, the extremities of the legs being angularly bent to form lugs, the central portion of the body having an elongated boss, a locking plate disposed upon said body and provided in one end portion with a longitudinally extending slot slidably engaging the sides of the boss, the lower surface of said end portion being engaged with the portion of the body surrounding the base of the boss, the other end portion of said locking plate having its lower surface positioned for engagement with a support or sash, the extremity of the last mentioned end portion being formed with an angularly disposed lug, and a rotatable cam mounted upon the boss and in all positions extending over and engaging the upper surface of the first mentioned end portion of the locking plate, the locking plate at the end of the slot being formed with an outwardly extending lug against which the cam bears, the second mentioned end portion of the locking plate being slideable flush with the spaced legs of the body.

In testimony whereof I hereunto affix my signature in the presence of two witnesses.

MAYNARD E. PENQUITE.

Witnesses:

M. C. LYDDANE,
M. R. WILSON.
